**Günther Philip Wild-
Wiedersheim & Söhne**

UNITED STATES PATENT OFFICE.

GÜNTHER PHILIP WILD, OF PHILADELPHIA, PENNSYLVANIA.

BRAKE FOR TALKING-MACHINES.

1,072,066.

Specification of Letters Patent. Patented Sept. 2, 1913.

Application filed February 1, 1912. Serial No. 674,764.

To all whom it may concern:

Be it known that I, GÜNTHER PHILIP WILD, a citizen of the United States, residing in the city and county of Philadelphia, 5 State of Pennsylvania, have invented a new and useful Brake for Talking-Machines, of which the following is a specification.

My invention consists of improvements on the brake attachment for talking machines for which Letters Patent No. 1,001,171 10 were issued to Frederick W. Schmidt on August 22nd, 1911.

It further consists of an improved construction of the brake-mechanism in such 15 attachment.

It further consists of other novel features of construction, all as will be hereinafter fully set forth.

The annexed drawings and the following 20 description set forth in detail one mechanical form embodying the invention, such detail construction being but one of various mechanical forms in which the principle of the invention may be used.

25 In said annexed drawings—Figure 1 represents a top plan view, somewhat diagrammatic, of a talking machine provided with my improvement. Fig. 2 represents a section of the finder-bar and its support.

30 Fig. 3 represents a detail plan view of the end of the blank from which the finder-bar is formed. Fig. 4 represents a vertical section of the brake. Fig. 5 represents a horizontal section of the brake and a detail plan 35 view of the associated parts of the brake device with the brake withdrawn. Fig. 6 represents a similar view with the brake set.

Similar numerals of reference indicate 40 corresponding parts in the figures.

Referring to the drawings, the reference numeral 1 indicates the casing or cabinet of the talking machine, upon which the record-carrier or turntable, 2, is rotatably mounted 45 to carry the record, 3. The machine has the usual tapering tone-arm or tone-tube, 4, at the free outer end of which is the sound-box, 5. All of said elements are of the usual or any approved construction employed in talking machines.

A hollow post, 6, is secured upon the top 50 of the cabinet, like in the above-recited patent, and a split plug, 7, fits in the same and has a shouldered head, 8, into which is 55 threaded a clamping-screw, 9, which clamps the longitudinally slotted finder-bar, 10, all

as in the above patent. In the present instance, the finder-bar is curved and has an opening, 11, at its outer free end. A spring, 12, is secured to the upper side of the bar and carries at its outer free end a needle, 13, which registers with and may pass through the opening in the end of the bar. A finger-piece, 14, is secured upon the outer end of the spring to afford a proper hold for the finger to depress the finder-needle. A lug, 15, is formed integral with the finder-bar and is bent upward, and a contact-screw, 16, is threaded through such lug. The distance between the needle and the point of the contact-screw is the same as that between the stylus of the sound-box and the point where the latter will contact with the contact-screw, when the tone-arm is brought toward the finder-arm.

A base-plate, 17, is secured upon the top of the cabinet and near the turntable, and said plate has annular ribs, 18, struck out around openings, 19. A casing, 20, rests upon an insulating plate, 21, upon the base-plate, and screws, 22, pass through metallic washers, 23, insulating washers, 24, and the openings in the base-plate, into the insulating plate and the casing, thus securing the latter upon the base-plate. A bolt, 25, 80 slides within the casing, and a spring, 26, within the casing bears against the rear end of said bolt. A brake-plug, 27, of leather or similar material, is secured in the end of the bolt to bear against and exert 85 braking friction against the turntable when the bolt is pushed outward by the spring. A knob, 28, is screwed into the bolt and slides in a slot, 29, in the casing, and the bolt may be manipulated by said knob. A 90 tooth, 30, projects from the side of the bolt and slides in a slot, 31, in the casing, and said tooth may be engaged by a detent, 32, upon an armature, 33, of two electro-magnets, 34. The armature is formed with ears, 100 35, bent away from the body of the same and mounted on a post, 36, around which is wound a spring, 37, normally tending to force the armature away from the magnets and against a stop, 38. The circuit consists 105 of a battery, 39, from which a wire, 40, passes to the electro-magnets and thence to the bolt-casing through a binding-screw, 43, in the end of the same. When the tooth of the brake-bolt engages the detent of the 110 armature, the current passes from the brake-bolt to the armature and a wire, 41, is con-

nected to said armature, which latter wire is connected to the pivot-post of the finder-bar. The opposite terminal wire, 42, of the battery-circuit is connected to the tone-arm.

5 When the slotted finder-bar is adjusted to the machine, which, like in the device of the above-mentioned patented structure, is only necessary when the attachment is adjusted to the machine, and a record is placed on the 10 turn-table, the needle is brought into register with the last groove of the record and is turntable, the needle is brought into register of the needle registers with the inner end of such groove. When the pressure upon the 15 finger piece is relieved, the needle is withdrawn by the spring, and the talking-machine may be started by pulling the brake-bolt back by means of its knob, until the tooth of the bolt is engaged by the detent of 20 the armature. When the stylus of the sound-box arrives at the end of the groove in the record, the tone-arm contacts with the contact-screw upon the finder-bar, closing the circuit and energizing the electro-magnet, 25 which causes the armature to be withdrawn from engagement with the tooth upon the brake-bolt, allowing the spring of the latter to force it into contact with the turntable, stopping the latter. When the 30 armature is withdrawn from engagement with the tooth upon the bolt, the current, which has been passed through the bolt and armature while the tooth and detent were in engagement, is broken, and the armature 35 flies back against its stop. A slight arc is liable to be formed when the circuit is broken by withdrawing the armature from engagement with the tooth or contact-piece of the brake-bolt, between said tooth and the 40 detent upon the armature, which gradually oxidizes the contact points of said parts and produces bad contact or eventually entirely destroys the same. By constructing the armature with the projecting detent which is 45 directly in the path of the tooth upon the brake-bolt when the armature is released from the magnets, the tooth and detent will exert a wiping action upon each other, so that any oxidized film which may have been 50 formed upon the contact points of said elements will be removed each time the brake is set.

By carrying the circuit through the brake-bolt and armature, a simple and direct contact is made and the mechanism is exceedingly simple, inexpensive of manufacture and not liable to get out of order.

Other modes of applying the principle of my invention may be employed for the mode

herein explained. Change may therefore be 60 made as regards the mechanism thus disclosed, provided the principles of construction set forth, respectively, in the following claims are employed.

Having thus described my invention, what 65 I claim as new and desire to secure by Letters Patent, is:—

1. In a braking attachment for talking machines, a rotatable member, a spring-actuated brake-bolt adapted for engagement 70 with said member, an electro-magnet having one terminal of its winding in constant electrical connection with said bolt, an armature formed with a detent adapted to engage and form direct electrical contact when in released position with said brake-bolt, a spring connected to move said armature away from said magnet, an electric circuit constantly connected to said armature and to the other terminal of the magnet-winding, and means 75 for positively opening and closing said circuit.

2. In a braking attachment for talking machines, a rotatable member, an insulated casing, a spring-actuated brake-bolt, adapted 80 for engagement with said member, sliding within and in constant electrical contact with said casing, means for retracting said bolt, an electro-magnet having one terminal of its winding in constant contact with said 85 casing, an armature formed with a detent projecting to engage and form direct electrical contact when in released position with the brake-bolt, a spring connected to move said armature away from said magnet, an electric circuit constantly connected to such 90 armature and to the other terminal of the electro-magnet, and means for positively 95 opening and closing said circuit.

3. In a brake for talking machines, a rotatable member, an electric circuit, positively actuated means for closing and opening said circuit, a brake bolt constantly connected in said circuit and having means for automatically throwing it into engagement with said member and for positively retracting it, an armature constantly connected in said circuit and having detent means for engaging when in released position the retracted 100 brake-bolt and for thus making direct electrical contact with the same, and means for automatically moving said armature into released position.

GÜNTHER PHILIP WILD.
